UNITED STATES PATENT OFFICE.

CHARLES A. RUTHERFORD, OF KAW, OKLAHOMA.

SEEDER ATTACHMENT FOR CULTIVATORS.

1,152,224.

Specification of Letters Patent. Patented Aug. 31, 1915.

Application filed July 18, 1914. Serial No. 851,778.

To all whom it may concern:

Be it known that I, CHARLES A. RUTHERFORD, a citizen of the United States, residing at Kaw, in the county of Kay and State of Oklahoma, have invented certain new and useful Improvements in Seeder Attachments for Cultivators, of which the following is a specification, reference being had to the accompanying drawings.

This invention relates to new and useful improvements in attachments for cultivators and more particularly to a seeder attachment for corn, peas and any suitable grain which can be used in a corn planter, the main object of the present invention being the provision of a planting attachment which can be readily applied to a cultivator or removed therefrom and which is actuated through means attached to one of the cultivator wheels.

Another object of the present invention is the provision of a cultivator attachment of the above character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claim.

In the accompanying drawings forming a part of this application, Figure 1 is a rear elevation illustrating a planter attachment constructed in accordance with my invention. Fig. 2 is a side elevation. Fig. 3 is a top plan view. Fig. 4 is a bottom plan view. Fig. 5 is a detail transverse sectional view. Fig. 6 is a plan view of the rotatable plate. Fig. 7 is a transverse sectional view through the operating shaft illustrating the mounting of the sliding sleeve. Fig. 8 is a side elevation of the clamping bolts used to fasten the sprocket to the cultivator wheel; and Fig. 9 is a side elevation of one of the yieldable tongues illustrating the mounting of the same.

Referring more particularly to the drawings, 1 indicates a cultivator frame, and 2 indicates the axle supporting the same, the ends of which are bent downwardly and disposed in a vertical position, as shown at 3 and their extreme ends bent at right angles to the vertical portions 3 to form spindles,

upon which the supporting wheels 4 are mounted.

My improved seeder attachment is preferably removably attached to the vertical portion 3 of the axle and includes a substantially circular body member 5 having formed upon one face thereof a bearing 6 adapted to receive a portion of the vertical member 3 which is securely held in position by means of the clamping block 7. The body 5 of the attachment is provided with a central opening 8 which is preferably threaded upon its interior, the purpose of which will be hereinafter more fully set forth. Rotatably mounted within the body is a plate 9 having a series of openings 10 formed therein which are adapted to register with a similar opening 11 formed in the bottom of the body 5, whereby the corn, peas or other grain may pass therethrough and into the hopper 12 and from thence into the boot 13. In order to securely retain the plate 8 in its operative position, I provide a casting 14 which is mounted within the upper portion of the body and securely held in position by means of a wing nut 15 having a screw 16 formed integral therewith and adapted to extend through the center of the casting and extend through the opening 8.

Pivottally mounted within a portion of the casting 14 are the yieldable tongues 17; the inner ends of which bear upon the coil spring 18, so as to yieldably retain the outer ends thereof into engagement with the rotatable plate 9. These tongues are inclosed and securely held in place by means of a cover 19 which is preferably of a design to entirely inclose the tongues and is securely held in position by means of a bolt 20 which extends through the casting 14 and through the cover 19. The casting 14 is provided upon its periphery with a lug 21 which is adapted to be inserted within a suitable recess 22 formed in the inner side wall of the body 5, to prevent rotary movement of the casting when in its operative position. Secured to the upper portion of the body is the hopper 23 which is securely held in position by means of the bolts 24, said hopper being provided with a hinged cover 25, whereby the device may be readily filled after being emptied.

Projecting downwardly from the bottom of the body 5, are the spaced bearings 26 arranged at diametrically opposite points upon the lower side of the body and mounted

for rotation therein, is a shaft 27 upon one end of which is mounted a sprocket 28, around which is adapted to extend a chain 29, said chain extending around a second 5 sprocket 30 which is supported upon the inner side of one of the wheels 4. The sprocket 30 is securely held in position by means of the hook bolts 31, the threaded ends of which are arranged within suitable 10 openings in the sprocket wheels, while the hooked ends thereof are engaged with the spokes of the wheel 4, whereby the tightening of the nuts carried by said bolts will clamp the sprocket securely to the wheel. 15 Mounted upon the shaft 27 and arranged in spaced relation with the sprocket 28, is a bevel gear 32 which is adapted to mesh with the annular gear 33 formed upon the inner face of the plate 9, whereby the rotary movement 20 of the shaft 27 will actuate the gear and rotate the plate 9 within the body 5.

Formed integral with the gear 32 is a sleeve 34 having a clutch face 35 adapted to engage with the clutch face formed upon the 25 movable sleeve 36. The sleeve 36 is provided with an elongated opening 37 adapted to receive a lug 38 formed upon the shaft 27 whereby to prevent rotary movement of the sleeve with respect to the shaft. Thus, when 30 the clutch faces of the two sleeves 34 and 36 are engaged, the sleeve 36 is provided upon its end opposite the clutch face with an annular flange 39, the purpose of which will be hereinafter more fully set forth. 35 Pivots connected to the lug 40, at one side of the body 5, is a lever 41 which extends transversely across the bottom of the body and is movable within a rack 42 which is suspended from the lower end of the body 40 and is provided with a plurality of teeth 43 which are adapted to be engaged by a spring actuated catch 44 to retain the lever in various adjusted positions.

A U-shaped member 45 is carried by the 45 lever and is adapted to engage with the flange 39 of the sleeve 36 to move the sleeve longitudinally upon the shaft 27 and engage or disengage the clutch members whereby the operating mechanism may be drawn into 50 or out of engagement with the driving mechanism. From this it will be apparent that upon inward movement of the sleeve 36, the clutch faces will be disengaged so as to disconnect the planting mechanism from the driving mechanism, but when it is desired to

connect the planting mechanism with the driving mechanism, of the cultivator, the lever is shifted to slide the sleeve 36 longitudinally upon the shaft and engage the two clutch faces. 60

It will be apparent from the above that my improved planter may be quickly and readily attached to various forms of cultivators and, at the same time it is extremely simple in construction and can be manufactured and placed upon the market at a comparatively low cost. 65

While I have shown and described the preferred form of my invention, it will be obvious that various changes in the details of construction and in the proportions may be resorted to for successfully carrying my invention into practice, without sacrificing any of the novel features or departing from the scope of the invention, as defined by the 75 appended claim.

Having thus described this invention, what I claim is:—

A device of the class described including a body, a plate mounted for rotation therein, a casting carried by the plate, yieldable tongues mounted within said casting, a coil spring disposed between the inner ends of each of the tongues and the casting, and the outer ends of said tongues engaging the rotatable plate, an annular gear formed on the lower face of the plate contiguous with the edge thereof, an operating shaft extending across the lower face of the body, a gear loosely mounted thereon adapted to engage with the annular gear, a clutch carried by the second gear, a second clutch movable upon the shaft, means carried by the shaft and coacting with the second clutch member to rotate the same with the shaft, a pivoted lever carried by the body and having connection with the second clutch member whereby to engage and disengage said clutch member, a rack carried by the body, and a spring actuated catch carried by the lever adapted for engagement with the rack whereby to retain said clutch members into or out of engagement. 90

In testimony whereof I hereunto affix my signature in the presence of two witnesses. 100

CHARLES A. RUTHERFORD.
